US00D893463S

(12) **United States Design Patent** (10) **Patent No.:** **US D893,463 S**
(45) **Date of Patent:** **** Aug. 18, 2020**

(54) **WALL MOUNT FOR AN AUDIO DEVICE**

(71) Applicant: **Sonos, Inc.**, Santa Barbara, CA (US)

(72) Inventors: **Aki Laine**, Santa Barbara, CA (US);
Edward Mitchell, Thousand Oaks, CA (US);
Philippe Vossel, Wuppertal (DE)

(73) Assignee: **Sonos, Inc.**, Santa Barbara, CA (US)

(***) Term: **15 Years**

(21) Appl. No.: **29/711,043**

(22) Filed: **Oct. 28, 2019**

Related U.S. Application Data

(63) Continuation of application No. 29/649,645, filed on May 31, 2018, now Pat. No. Des. 870,082.
